United States Patent Office

Des. 184,641
Patented Mar. 17, 1959

184,641

AIRSHIP

Alex A. Rommel, Fresno, Calif.

Application August 26, 1957, Serial No. 47,509

Term of patent 14 years

(Cl. D71—1)

FIG. 1.

FIG. 2.

FIG. 3.

Fig. 1 is a top plan view of an airship showing my new design.

Fig. 2 is a front elevation of the airship.

Fig. 3 is a side elevation thereof. The opposite side of the airship from that shown is the same in appearance as the side shown.

I claim:

The ornamental design for an airship, as shown and described.
